GAUGING DEVICE

Filed May 24, 1924

Patented June 8, 1926.

UNITED STATES PATENT OFFICE.

RENÉ E. DUPLESSIS, OF BEVERLY, MASSACHUSETTS, ASSIGNOR TO UNITED SHOE MACHINERY CORPORATION, OF PATERSON, NEW JERSEY, A CORPORATION OF NEW JERSEY.

GAUGING DEVICE.

Application filed May 24, 1924. Serial No. 715,589.

This invention relates to trimming machines and is illustrated as embodied in a machine especially designed to be used to trim the edge of an insole attached to a last before the upper has been placed on the last.

In the majority of shoe factories the prevailing and most economical practice of fitting an insole to a last is to die out the 10 insole so that its forepart will fit the last and so that its heel-seat will be longer and wider than that of the last, and to register the forepart and let the heel-seat project beyond the last when driving the tacks by 15 which the insole is temporarily secured to the last. While this practice permits fitting the forepart of the insole to the last it necessitates trimming the surplus material from the margin of the insole around the heel-seat after the last and insole have been 20 assembled as above described. Incidentally to performing this trimming operation by the machines most commonly used, shoulders are formed on the opposite edges of the 25 shank portion of the insole at the points where the trimming begins and ends, and the formation of such shoulders is so objectionable that various devices have been designed to avoid it. For example, United States 30 Letters Patent No. 1,415,966, granted May 16, 1922, on application of H. D. Webb, illustrates a device designed to overcome the difficulty in question by leading the trimming cut gradually from the edge of the 35 insole toward the edge of the heel-seat of the last as the trimming progresses along one side from the breast line toward the back of the heel, and by leading the trimming cut gradually from the edge of the 40 heel-seat of the last toward the original edge of the insole as the trimming progresses along the other side from the back of the heel toward the breast line.

The patented device comprises a gauge 45 having two abutments spaced apart and arranged in tandem relation to slide on the perimeter of the last. These abutments, working in cooperation with each other, utilize the variant curvature of the last to 50 effect a gradual deviation of the course of trimming from the edge of the sole toward the edge of the heel-seat of the last and vice versa. To keep the maximum depth of trimming within the desired limit for all

sizes with the patented device it was found 55 necessary to provide two interchangeable gauges to take care of the whole range of sizes, that is to say, a gauge of relatively large proportions for the larger sizes, and a gauge of relatively small proportions for 60 the smaller sizes, the essential difference being in the spacing of the two abutments one from the other.

In view of the aforesaid conditions an object of this invention is to provide improved 65 gauging means which, without sacrificing any of the advantages of a device of the type above referred to, will insure the desired course or depth of trimming around the back of the heel-seat irrespective of the size of 70 the last. In other words, this object is to obtain the aforesaid desired results for all sizes with the same gauging means.

A feature of the invention by which the 75 above object is attained consists in a combination comprising two distinct gauging means one of which is constructed and arranged to lead the course of trimming gradually toward and from the edge of the last at the sides, and the other of which is constructed and arranged to function only while trimming around the back of the heel-seat and there to limit the depth of trimming to any desired course and lead that course parallel to the edge of the last.

According to another novel feature of the invention, the illustrated construction provides a gauging device comprising three abutments arranged in a series, the intermediate abutment being offset inwardly 80 from a line tangential to the two terminal abutments and adapted to engage only the back of the heel, and that only when the back of the heel is between the two terminal abutments, while the latter are so spaced 85 from each other as to hold the last out of contact with the intermediate abutment when one side or the other of the last is in contact with them. By virtue of this feature the terminal abutments utilize the variant 90 curvature of the last to lead the course of trimming gradually from the edge of the insole inwardly and finally outwardly, whereas the intermediate abutment controls 95 the course of trimming while progressing around the back of the heel-seat where the curvature is greatest. Thus, while the terminal abutments may be arranged to afford 100 105

the desired gradual gauging effect for all sizes the intermediate abutment is always a safeguard to prevent trimming too deeply, even on the smallest size, while progressing 5 around the back of the heel.

Another novel feature consists in provisions for adjusting the three abutments collectively toward and from the working point of the trimming cutter to regulate the depth 10 of trimming throughout the entire course, and still another novel feature consists in provisions for adjusting the two terminal abutments relatively to the intermediate abutment to regulate the course of trimming 15 at the sides without altering the extreme depth of trimming around the back of the heel as determined by the intermediate abutment.

Other features of the invention are herein- 20 after described and claimed and are illustrated by the accompanying drawings.

Referring to the drawings:

Fig. 1 is an elevation of a well known type 25 of insole heel-seat trimming machine equipped with gauging means of a preferred construction embodying the present invention;

Fig. 2 is a similar elevation on a larger 30 scale of the gauging means shown in Fig. 1 and shows a stage of trimming where the intermediate abutment alone is functioning;

Fig. 3 is a perspective view of said gauging 35 means;

Fig. 4 is a view similar to Fig. 2 of a fragment 40 of the gauging means and represents that stage of trimming where the two terminal gauging abutments are about to take control away from the intermediate abutment;

Fig. 5 is a view similar to Fig. 4 showing 45 the final stage of trimming in which the two terminal abutments hold the last away from the intermediate abutment;

Fig. 6 is a sectional view including fragments 50 of the heel end of a last, an insole, a trimming cutter and gauging devices for controlling the course of trimming, the working conditions represented by this figure corresponding to those represented in Fig. 2;

Fig. 7 is a view similar to Fig. 6 excepting 55 that the working conditions correspond to those shown in Fig. 5 (see line VII—VII of Fig. 5); and

Fig. 8 is a plan view of the heel-seat end of 60 an insole before being trimmed to the last, and includes broken lines representing the outline of the heel-seat of the last and broken lines representing the course along which the trimming is led by the gauging means shown in the other figures.

With the exception of the gauging means 65 hereinafter described the illustrated trimming machine is of the same type and embodies the same construction as that more fully disclosed in United States Letters Pat-

ent No. 1,295,965, granted March 4, 1919, on an application of Brown and Macleod. This machine comprises a column 10 the lower portion of which is omitted from the drawing to save space. This column furnishes 70 bearings for a horizontal shaft 12 at the front end of which is a toothed cutter 14 of well-known form for trimming the edge of an insole. The machine also comprises a jack or arm 16 arranged to swing on a pin 75 18 to guide the last 20 toward and from the cutter 14. The jack is therefore provided with a last pin 22 adapted to occupy the usual last-pin socket 24. Other elements carried by the jack 16 include mechanism for 80 clamping the heel-seat portion of an insole 26 against the corresponding portion of the last and for holding the last firmly on the pin 22, but inasmuch as said clamping mechanism is fully disclosed in said Patent 85 1,295,965 it will not be necessary to describe it in detail in this instance. It is to be understood, however, that the said clamping mechanism is capable of turning with the last as the latter swings about the axis of the 90 pin 22. The pin 18 on which the jack 16 swings forms a part of a universal point which includes the pin 28 extending at right angles to the pin 18 and arranged in a bearing afforded by a fixture 30. The jack has a 95 limited movement about the axis of pin 28 to provide for different heights of lasts and for the curvatures of the bottoms of the last, while it may also swing about the pin 18 to guide the last toward and from the 100 cutter.

Although insoles are ordinarily died out approximately to the desired shapes and sizes it is customary to give them a little extra length and width at the heel end to provide for slight discrepancies between the outline of the last and the outline of the insole. The assembler locates the insole relatively to the last with regard only to the forepart, and drives two or more tacks to 105 fasten the insole temporarily to the last. As a result of this assembling practice the heel end of an insole almost invariably projects beyond the heel end of the last and the sides of the heel-seat portion usually project beyond the heel-seat of the last, and whether the extent of projection is much or little, good shoemaking practice requires the length of the insole to be the same as that of the last, even though the heel-seat portion of the insole be wider than that of the last. As to the latter, good practice requires that if there be any extra width in the heel seat portion of the insole it should be only in the forward part and the outline of the 110 insole should merge gradually into the outline of the heel-seat of the last at points from one half an inch to an inch forward of the extreme heel end, so that the outline of the insole will conform exactly to the outline 115 120 125 130

of the last throughout the arc of nearly 180 degrees of relatively short curvature around the back of the last.

The gauging means now about to be described not only satisfies the requirements last explained but provides for suitable adjustments to satisfy these requirements throughout the entire range of sizes. As shown best by Fig. 3, the illustrated gauging means comprises gauging members 32 and 34 which are respectively stationary and oscillatory but both adjustable. The member 32 provides a convex abutment 36 for engaging the heel end of the last as shown by Figs. 2 and 6, while the member 34 provides two spaced abutments 38, 38 for engaging the sides of the last in tandem relation as shown best by Fig. 5. These three abutments are arranged in a series of which 38, 38 are hereinafter termed the terminal abutments and 36 is termed the intermediate abutment. The intermediate abutment is offset backwardly from a line tangential to the two terminal abutments, and its distance from said line is capable of being varied by relatively adjusting the two gauging members 32, 34 as hereinafter explained.

The member 32 is adjustably mounted in a bracket 40 (Fig. 1) fastened to the column 10. It is located in front of the trimming cutter 14 and its lines of adjustment are at right angles to the axis of the cutter. Ribs 42 (Fig. 3) are formed on the member 32 to slide in grooves formed in said bracket, and the adjusting movement of the gauge member is obtained by a screw 44. The screw turns freely in the bracket 40 and engages screw-threads tapped in the member 32.

A lip 46 formed on the member 32 is arranged to project between the last and the margin of the sole, as shown in Figs. 6 and 7, and is effective to register the last relatively to the gauging abutments to register the sole relatively to the cutter, and to brace the margin of the sole against buckling.

The oscillatory gauging member 34 is carried by an adjustable holder 48 and is connected thereto by a pivot pin 50 (see Fig. 3). The shank portion 52 of the holder 48 is arranged to slide in a groove formed in a fitting 54 affixed to the gauging member 32. The lines of individual adjustment of the gauging member 34 are parallel to those of the member 32, and relative adjustment of the two gauging members is obtained by an adjusting screw 56 connected to the fitting 54 so that it may turn but have no relative axial movement, while the holder 48 is bored and tapped to engage the thread of the screw. By turning the screw 56 the oscillatory member 34 comprising the two terminal abutments 38 may be adjusted relatively to the intermediate abutment 36, whereas turning the adjusting screw 44 does

not alter the relation between the gauging members 32 and 34 but adjusts them collectively.

The pivotal mounting of the gauging member 34, as provided by the pivot 50, enables that member to oscillate relatively to the gauging member 32 so that both abutments 38, 38 may remain in contact with the last while it is their duty to control the course of trimming. In other words, it provides a compensatory movement of the abutments 38, 38 by which they are enabled to follow the last as the latter is turned about the last pin 22. No such movement of the intermediate abutment 36 is necessary but the latter is preferably extended in an arc concentric to the axis of the cutter, since the point of contact between the last and that abutment will shift slightly in consequence of turning the last while that abutment is functioning on the back of the last.

A light spring 58 of wire normally supports the gauging member 34 in its median position. The mid-portion of this spring is loosely coiled about a screw 60 carried by the member 34, while one end projects into a hole in that member. The other end bears against the holder 48.

Referring to Fig. 8, the initial outline of an insole 26 is represented by a continuous line, the outline of the heel-seat of the last is represented by a broken line 62, and the desired course of trimming is indicated in part by broken lines 64, 64 and in part by the broken line 62 connecting the two lines 64 around the back of the heel. From this showing it is apparent that the lines 64 merge smoothly into the original cutline of the insole near the forward end of the heel-seat and at the other end into a curve conforming to the outline of the heel-end of the last. To set the gauging members to obtain this course of trimming the member 32 will first be adjusted by turning the screw 44 until the abutment 36 occupies the desired relation to the teeth of the cutter. For example, as shown by Fig. 6, the abutment 36 is adjusted to register with the teeth of the cutter to insure trimming the insole flush with the outline of the last around the back of the heel-seat, and while flush trimming at this point is usually preferable, it is possible to shift the course of trimming to the inside or to the outside of the outline of the last by giving the abutment 36 other positions of adjustment. In any case, as the effective diameter of the cutter grows gradually less in consequence of repeated sharpening operations the abutment 36 may be adjusted to compensate for its decreasing diameter.

Having adjusted the gauging member 32 to the desired position relatively to the cutter, the only other preliminary step is to adjust the gauging member 34 relatively to the

member 32 according to the size of the last or according to the points at which it is desired to join the courses 64 of trimming at the sides with the course of trimming 5 around the end. In other words, the converging courses of trimming represented by the broken lines 64, 64 may be shifted toward and from the back of the heel by relatively adjusting the gauging member 34.

Having adjusted the two gauging members to determine a course of trimming as above explained and as represented by Fig. 8, the abutments 36, 38, 38 function as follows: A last with an insole to be trimmed is mounted on the last pin 22, the clamping means carried by the jack 16 is set up to clamp the insole firmly against the last and the operative, grasping the handles 66 (Fig. 1) in the left hand and the forepart of the last in the right hand, first swings the toe of the last upwardly and then swings the jack toward the cutter. The left side of the last is thus brought into engagement with the terminal abutments 38, 38 and the cutter 25 begins to operate on the insole at a point adjacent to the arrow in Fig. 8. To cause the trimming to progress in the direction of this arrow the operative swings the toe of the last in the direction indicated by the arrow in Fig. 1, at the same time maintaining pressure of the last against the abutments 38. As the last turns about the pin 22 it slides on the abutments 38 and the point of trimming gradually approaches the outline 35 of the heel-seat of the last by following the course indicated by the broken line 64 at the top of Fig. 8. This gradual approach to the edge of the last is controlled by the gradually increasing convexity of the last as the trimming progresses from the starting point toward the back of the heel, the increasing convexity permitting the last to enter gradually the gap between the abutments 38, 38.

When the trimming has progressed about 45 half way from the starting point to the back of the heel (the exact distance may be varied by adjusting the gauging members 32 and 34) the last touches the abutment 36 between the abutments 38 (see Fig. 4) and at 50 this point the maximum depth of trimming is reached, the abutments 38, 38 cease to function, and the intermediate abutment 36 takes control of the course of trimming and maintains such control until the trimming has progressed to the corresponding point on 55 the other side of the longitudinal median line of the last. While the trimming is progressing around the back of the heel under control of the abutment 36 it necessarily follows a course parallel to, if not actually coincident with, the edge of the heel-seat of 60 the last, since the varying curvature of the last has no effect in altering the depth of trimming so long as the depth is limited by 65 the single abutment 36. In the meantime

the gauging member 34 merely oscillates idly as required by the turning of the last, for although it is not at this time functioning to control the depth of trimming at least one of its abutments 38 will be in contact with the side of the last and it will follow the movement of the last until that point is reached at the opposite side where the diminished convexity of the last restores the gauging to the control of the two abutments 38, 38. Continuing from this point the abutments 38, 38 divert the course of trimming gradually away from the edge of the last as indicated by the broken line 64 at the lower side of Fig. 8, and the depth of trimming is gradually decreased until the trimmed edge merges with the original edge at or near the front of the heel-seat.

Having thus described my invention, what I claim as new and desire to secure by Letters Patent of the United States is:

1. In a machine for controlling an operation by a contour of a last, an operating tool, and gauging means comprising three abutments arranged in a series to contact with said contour, the intermediate one of said abutments being offset backwardly from a line tangential to the terminal abutments and arranged to engage only the end of the last and that only when it is between said terminal abutments.

2. In a machine for controlling an operation by a contour of a last, an operating tool, and gauging means comprising three abutments arranged in a series to contact with said contour, the intermediate one of said abutments being offset backwardly from a line tangential to the terminal abutments and arranged to engage the end of the last when said end is between said terminal abutments, and said terminal abutments being arranged to function simultaneously by engaging first one side of the last and then the other.

3. In a machine for operating progressively upon an article of work in fixed relation to a pattern having a curved contour, a tool arranged to operate on the article of work, and gauging means comprising three abutments arranged to engage said contour, two of said abutments being arranged to function simultaneously where the curvature of said contour is relatively gradual, and the other being arranged to function where the curvature is relatively sharp.

4. In a machine for trimming the edge of a sole attached to a last, trimming means, gauging means arranged to abut the heel of the last to lead the course of trimming gradually inwardly at one side of the heel-seat and gradually outwardly at the other side, and gauging means arranged to abut the back of the last to limit the depth of trimming around the heel end.

5. In a machine for trimming the edge of

- a sole attached to a last, trimming means, gauging means comprising two cooperative abutments spaced apart and arranged to abut the heel of the last in tandem relation to lead the course of trimming gradually inwardly at one side of the heel-seat and gradually outwardly at the other side, and an abutment arranged to abut the last between said two abutments to limit the depth of trimming around the heel end. 6. In a machine for trimming the edge of a sole attached to a last, trimming means, gauging means comprising two cooperative movable abutments spaced apart and arranged to abut the heel of the last to lead the course of trimming gradually inwardly at one side of the heel-seat and gradually outwardly at the other side, and an abutment arranged to abut the last between said two abutments to limit the depth of trimming around the heel end. 7. In a machine for trimming the edge of a sole attached to a last, trimming means, and gauging means comprising three abutments arranged in a series, the intermediate one of said abutments being arranged to abut the back of the last to limit the depth of trimming around the end of the heel and the two others being arranged to abut the last simultaneously to lead the course of trimming gradually to and from that determined by said intermediate one. 8. In a machine for trimming the edge of a sole attached to a last, trimming means, gauging means arranged to abut the back of the last to lead the trimming at the heel end along a course parallel to the edge of the last, and gauging means arranged to engage two points of the last simultaneously to lead the trimming at one side gradually toward said edge and at the other side gradually away from said edge. 9. In a machine for trimming the edge of a sole attached to a last, trimming means, and gauging means comprising three abutments arranged in a series, the two terminal abutments of said series being arranged to run simultaneously on the last to control the trimming along the sides of the heel-seat of the sole, and the intermediate abutment being offset from a line tangential to said terminal abutments to control the course of trimming around the back of the heel-seat. 10. In a machine for trimming the edge of a sole attached to a last, trimming means, and gauging means comprising three abutments arranged in a series, the two terminal abutments of said series being movable and arranged to engage the last to control the courses of trimming along the sides of the heel-seat, and the intermediate abutment being stationary and arranged to engage the back of the last to control the course of trimming around the back of the heel-seat. 11. In a machine for trimming the edge of a sole attached to a last, trimming means, gauging means arranged to engage the last to lead the trimming around the heel end along a course conforming to the contour of the last irrespective of the size of the last, and means arranged to engage the heel of the last at two separate points in tandem relation to lead the trimming gradually in to said course at one side of the heel and gradually out from said course at the other side irrespective of the size of the last. 12. In a machine for trimming the edge of a sole attached to a last, trimming means, gauging means including two cooperative movable abutments and a stationary abutment all arranged to engage the perimeter of the heel-part of the last, said movable abutments being arranged to lead the course of trimming gradually inwardly at one side and gradually outwardly at the other side, and said stationary abutment being arranged to limit the depth of trimming around the heel end. 13. In a machine for trimming the edge of a sole attached to a last, trimming means, a gauging device constructed and arranged to effect a divergent course of trimming at the sides of the heel-seat, and a gauging device arranged to effect a non-divergent course of trimming around the heel end. 14. In a machine for trimming the edge of a sole attached to a last, trimming means, gauging means constructed and arranged to control the courses of trimming along the sides of the heel-seat portion, and gauging means constructed and arranged to control the course of trimming around the heel end, said two gauging means being relatively adjustable to determine the points where said side courses shall join said end course. 15. In a machine for trimming the edge of a sole attached to a last, trimming means, gauging means constructed and arranged to control the courses of trimming along the sides of the heel-seat portion, gauging means constructed and arranged to control the course of trimming around the heel end, said two gauging means being relatively adjustable to determine the points where said side courses shall join said end course, and means arranged to adjust said two gauging means collectively to regulate the closeness of trimming. 16. In a machine for trimming the edge of a sole attached to a last, trimming means, a gauging device comprising an abutment and a lip, said lip being formed and arranged to project between the last and the margin of the sole, and said abutment being arranged to abut the back of the last to determine a course of trimming around the heel end, and gauging means arranged to abut the sides of the heel of the last to divert the courses of trimming along the sides of the heel-seat.

17. In a machine for trimming the edge of a sole attached to a last, trimming means, a stationary gauging device comprising an abutment and a lip, said lip being formed and arranged to project between the last and the margin of the sole, and said abutment being arranged to abut the back of the last to control the course of trimming around the heel end, and movable gauging means arranged to abut the sides of the last to divert the courses of trimming along the sides of the heel-seat. 35
18. In a machine for trimming the edge of a sole attached to a last, trimming means, a gauging device formed and arranged to have a single point of contact with the back of the last to control the trimming around the heel end, said device having a lip formed to project between the last and the margin 40 of the sole, and a gauging device formed and arranged to have two separate points of contact in tandem relation with the last to lead the course of trimming gradually inwardly along one side of the heel-seat and gradually outwardly along the other side. 45
19. In a machine for trimming the edge of a sole attached to a last, trimming means, a stationary gauging device and a movable gauging device formed and arranged to function alternately to determine a course of trimming along the sides and around the back of the heel-seat. 50
20. In a machine for trimming the edge of a sole attached to a last, trimming means, a stationary gauging device and a movable gauging device formed and arranged to function alternately to determine a course of trimming along the sides and around the back of the heel-seat, said stationary device having a lip formed to project between the last and the margin of the sole. 55

21. In a machine for trimming the edge of a sole attached to a last, trimming means, an oscillatory gauging device formed and arranged to have two points of contact in tandem relation with the last to control the trimming along the sides of the heel-seat, and a stationary gauging device formed and arranged to have a single point of contact with the last to control the trimming around 60 the end of the heel-seat. 65

22. In a machine for trimming the edge of a sole attached to a last, trimming means, an oscillatory gauging device formed and arranged to have two points of contact in tandem relation with the last to control the trimming along the sides of the heel-seat, and a stationary gauging device formed and arranged to have a single point of contact with the last to control the trimming around 60 the end of the heel-seat, said stationary device having a lip formed arranged to project between the last and the margin of the sole. 65

In testimony whereof I have signed my name to this specification.

RENÉ E. DUPLESSIS.
